CLAIM

The ornamental design for a wet or dry wipe dispenser and container, as shown and described.

DESCRIPTION

FIG. 1 is a front perspective view of a wet or dry wipe dispenser and container, showing my new design;

FIG. 2 is a front view thereof;

FIG. 3 is a right side view thereof;

FIG. 4 is a rear view thereof;

FIG. 5 is a left side view thereof; and,

FIG. 6 is a top view thereof.

The bottom view does not comprise part of the claim.
